HOUSING FOR SNOW THROWER

Gerhard R. Plamper, Parma, Ohio, assignor to MTD
Products Inc., Cleveland, Ohio, a corporation of Ohio

Filed June 6, 1969, Ser. No. 17,545

Term of patent 14 years

Int. Cl. D15—99

U.S. Cl. D35—2

Fig. 1

Fig. 2

Fig. 3

Fig. 4

Fig. 5

Fig. 6

Fig. 7

FIG. 1 is a perspective view of a housing for snow thrower embodying my design, the housing being illustrated as mounted on a tractor or driving unit shown in broken lines for illustrative purposes only;

FIG. 2 is a front view of the housing;

FIG. 3 is one end view of the same;

FIG. 4 is an opposite end view of the same;

FIG. 5 is a top plan view of the same;

FIG. 6 is a bottom plan view of the same; and

FIG. 7 is a rear view of the same.

I claim:

The ornamental design for a housing for snow thrower, substantially as shown and described.
